(57) **CLAIM**

The ornamental design for an exterior surface of a cyclone
receptacle, as shown and described.

DESCRIPTION

FIG. 1 is a perspective view of an exterior surface of a cyclone
receptacle according to a first embodiment of the present
invention.

FIG. 2 is a front elevation view of the exterior surface of a
cyclone receptacle of FIG. 1.

FIG. 3 is a left side elevation view of the exterior surface of a
cyclone receptacle of FIG. 1.

FIG. 4 is a rear elevation view of the exterior surface of a
cyclone receptacle of FIG. 1.

FIG. 5 is a right side elevation view of the exterior surface of
a cyclone receptacle of FIG. 1.

FIG. 6 is a top plan view of the exterior surface of a cyclone
receptacle of FIG. 1.

FIG. 7 is a bottom plan view of the exterior surface of a
cyclone receptacle of FIG. 1.

FIG. 8 is a perspective view of an exterior surface of a cyclone
receptacle according to a second embodiment of the present
invention, the second embodiment being a mirror image of
the first embodiment.

FIG. 9 is a front elevation view of the exterior surface of a
cyclone receptacle of FIG. 8.

FIG. 10 is a left side elevation view of the exterior surface of a
cyclone receptacle of FIG. 8.

FIG. 11 is a rear elevation view of the exterior surface of a
cyclone receptacle of FIG. 8.

FIG. 12 is a right side elevation view of the exterior surface of
a cyclone receptacle of FIG. 8.

FIG. 13 is a top plan view of the exterior surface of a cyclone
receptacle of FIG. 8; and, FIG. 14 is a bottom plan view of the
exterior surface of a cyclone receptacle of FIG. 8.

In the drawings, broken lines indicate environmental structure
or boundaries that form no part of the claimed design.

1 Claim, 14 Drawing Sheets
